Patented Dec. 12, 1967

209,552

COOKWARE DISPLAY RACK OR SIMILAR ARTICLE

Elmer L. Reibold, Park Ridge, William W. Timpe, Prospect Heights, and Kasimer F. Panek, Broadview, Ill., assignors to E. L. Reibold Agency, Inc., Rosemont, Ill., a corporation of Illinois

Filed Apr. 11, 1967, Ser. No. 6,631

Term of patent 7 years

(Cl. D80—10)

FIG. 1

FIG. 3

FIG. 1 is a perspective view of a cookware display rack embodying our new design;

FIG. 2 is a reduced front elevational view thereof, and FIG. 3 is a reduced side elevational view thereof.

We claim:

The ornamental design for a cookware display rack or similar article, substantially as shown.
